Fig. 5

FIGURE 1 is a front elevational view of the display cabinet showing my new design, equipped with a canopy and with the outer door in the open, stored position.

FIGURE 2 is a front elevational view of the design of FIGURE 1 but showing the outer door in its closed position.

FIGURE 3 is an end elevation as viewed from either side of either of the FIGURES 1 and 2.

FIGURE 4 is a front elevational view showing my new design, without a canopy and with the outer door in its open, stored position.

FIGURE 5 is a front elevation similar to FIGURE 4 but showing the outer door in its closed position.

FIGURE 6 is an end elevation viewed from either side of FIGURES 4 and 5.

The sides opposite to those shown in the various figures are substantially the same as those shown in the respective figures.

The essential features of the design reside in the portions shown in full lines.

This application is a continuation-in-part application of my copending applications Serial Numbers D. 67,217 and D. 67,220 both of which were filed on October 23, 1961 and which have become abandoned since the filing of this application.

I claim:

The ornamental design for a display cabinet for gasoline service stations, as shown and described.
